LUBRICATING SYSTEM FOR SEWING MACHINES AND PARTS THEREOF

John P. Weis, Nyack, N. Y., assignor to Willcox & Gibbs Sewing Machine Company, New York, N. Y., a corporation of New York

Application November 18, 1935, Serial No. 50,460

10 Claims. (Cl. 112—256)

This invention relates to improvements in lubricating systems and parts thereof for sewing machines and to a method of making the same, and is a continuation in part of my application 5 Serial No. 11,488, filed March 16, 1935.

Lubrication of any high speed machine usually presents many problems. However, very special problems are involved in the lubrication of sewing machines, and especially those in which it is desired to obtain very high speeds. Because there are many moving parts in sewing machines, numerous bearings are required and it is highly important that each be lubricated properly. Further, because many of the parts have free ends 10 which are moved through a considerable path, heavy loads are imposed upon the bearings, and consequently they should be continuously and thoroughly lubricated.

In sewing machines it is highly important that 20 none of the lubricant reaches the work, either by: (1) leaking directly onto the work; (2) leaking onto the outer surface of the machine and being carried onto the work by the operator's hands; (3) getting out of the machine onto the 25 adjacent work bench upon which either the finished or unfinished work is placed. This desideratum will be appreciated when it is realized that high quality silks and other costly fabrics and materials are regularly operated upon 30 by sewing machines of this type.

It is an object of the present invention to provide a highly efficient lubricating system for sewing machines which will automatically and thoroughly lubricate all of the bearings and points 35 of friction in a more satisfactory manner than those heretofore provided so that extremely high speeds may be obtained and maintained, and so that there is no danger of the lubricant ever contacting with the materials either before, during, 40 or after the sewing operation.

It is another object of the present invention to provide a sewing machine in which it is not necessary for an operator to manually oil any of the bearings or operating parts.

45 Features resulting from the accomplishment of this desideratum and the attainment of these objects include the provision of a lubricating system for sewing machines adapted to:

(1) Force feed lubricant to practically all of 50 the many main operating bearings in a simple, economical, and expeditious manner, and to have these bearings literally run in a bath of oil without danger of reaching the materials being processed.

(2) Efficiently lubricate both the cutter and

needle operating mechanisms without danger of passing oil to the work, even though these mechanisms are close to the work as it is passed through the machine.

(3) Lubricate remote and less important bearings very efficiently, with a novel structure effecting a combined force and/or gravity feeding of the lubricant. 5

(4) Confine lubricant very thoroughly in a chamber forming a reservoir for lubricant and a 10 housing for practically all of the main driving mechanism by a novel inner and/or outer retaining structure.

(5) Apprise the operator at all times relative to whether and the extent to which lubricant is 15 being passed through the system.

(6) Efficiently store and pump lubricant, and also to effectively screen or filter the same.

(7) Permit the work plate to be moved quickly 20 into and out of operative and inoperative position relative to the main frame without using special tools to disconnect pipes, joints, or the like in the lubricating system.

(8) Deposit an infinitesimal amount of lubricant vapor on the sewing thread or threads, automatically, to minimize thread breakage. 25

(9) Pass oil vapor directly to bearings.

(10) Collect oil vapor which might otherwise be wasted or adversely deposited on the adjacent work holding bench supporting the sewing machine, and deposit the collected vapor on bearings of operating parts overlying the work plate, 30 to oil the latter automatically.

It is a further, and important, object of the present invention to provide a lubricating system 35 for sewing machines which will dispense with usual suspended pipes between various operating parts, with unsatisfactory soldered and threaded connections, which are often kinked, split, jarred loose, or otherwise adversely impaired, and one dispensing with the unsatisfactory use of oil conducting wicks. 40

Features resulting from the accomplishment of this object include: the provision of oil conducting ducts entirely within the top and bottom faces 45 of the top plate; in one form, the provision of integral oil conducting ducts cast within the main frame of the sewing machine; in another form, the provision of a system of oil conducting pipes cast directly within the main frame of the sewing machine; and, a novel method of casting a plurality of interconnected oil conducting pipes directly within the sewing machine frame, without danger of filling the pipes with the molten metal 50 of the casting.

Other objects, features, and advantages will appear hereinafter.

The detailed description which follows is under various headings to facilitate an understanding of the various mechanisms and their mode of operation, and to disclose the present improved lubricating system. The present invention is not limited to the details of construction and arrangement of parts illustrated and described herein, for the invention is capable of other embodiments in whole or part, in sewing machines other than those of overedge type, and the phraseology used is for the purpose of description and not of limitation.

First there is a brief description of the general structure and the various operating parts, and secondly a very detailed description of the novel lubricating system provided by the present invention.

Main frame and general structure

In its present preferred form, the sewing machine embodying the present invention comprises a main frame 20 having a bottom 21, and having front, rear, left side, and right side walls 22, 23, 24, and 25 respectively, preferably forming a reservoir 26 for lubricant 27. A plug 27' may be provided to occasionally draw off the lubricant. A glass insert 28 may be provided to indicate the level of lubricant in the reservoir. Rubber cork or other resilient plugs 29 in bosses

29' are provided to minimize vibration between the machine and bench.

A work plate 30 is supported on the main frame 20 by preferably spaced pivot connections 31, including suitable rearwardly projecting lugs 32 on the main frame 20 and cooperating lugs 33 on the work plate 30 with pointed studs 34 therebetween entering tapered holes 34', as may be seen best in Figs. 2 and 7.

The work plate 30 is movable about the pivot connections 31 into a raised inoperative position for repairs and adjustments, where it is held by a pin and slot connection 35 (Fig. 3), and into a lowered operative position where it is held by a catch 36 (Fig. 1).

In order to provide an effective oil seal between the main frame 20 and the work plate 30 and also to provide a very effective noise and vibration absorber, the present invention provides a cork, felt or like pad 37, preferably located in a suitable channel 38 in the top edge of the side walls 22 through 25. The underside of the work plate rests upon this pad. The side wall 25 is provided with a concave section 39 (see Figs. 1, 7, 9, and 10) with a coextensive pad 37 and channel 38 shaped like and underlying a bearing lug 40, to prevent oil-leakage.

The work plate 30, preferably, and as shown, is adapted to advantageously support a trimming mechanism 42, thread control mechanism 43, a presser device 44, and a trimming mechanism and presser device shifter 45 on its upper side, and to support a main drive shaft 46 and associated needle operating looper, differential feeding and main driving mechanisms 47, 48, 49, and 50 respectively on its underside. All of these mechanisms will now be described in sufficient detail to facilitate an understanding of the lubrication system of the present invention.

Main driving mechanism

The main driving mechanism 50, best seen in Figs. 3, 4, 5, 7, 9, and 10, preferably comprises a substantially one piece main drive shaft 46 having a split sleeve bearing 51 near the middle and having a ball bearing 52 at the right side and a similar ball bearing 53 on the left side.

These bearings 51, 52, 53 are supported relative to the work plate 30 in suitable coaxial bores 54, 55, and 56 either by a forced fit or any conventional holding screws, in depending walls 57, 58, and 59. If preferred, these solid bores may be conventional split bores with cap sections, as shown in my aforesaid application Serial No. 11,488, filed March 16, 1935.

Axial movement of the main drive shaft 46, seen best in Fig. 9, may be prevented by one or more of the following: the ends of the split bearing 51 engaging flanges on the main drive shaft; the flange 60 and pulley hub 61' engaging the bearing 52; the hub 62 and head 63 at the left end of the main drive shaft 46 engaging the bearing 53. The main drive pulley 61 is secured to the right end of the drive shaft in any suitable manner.

Although it would be possible to have the hub 62, head 63, and eccentric 64 integral with the remainder of the main drive shaft 46, the head and eccentric are preferably made separate and secured into extension 62' in the left hand end of the main drive shaft by any suitable holding means. Oil retainers 65 may be provided in the ball bearings 52 and 53 to prevent oil from escaping. The main drive shaft is provided with a feed lift crank 66 and an upper looper crank 75

67 on the left side of the bearing 51, and with a combination needle and trimmer operating crank 68 and a lower looper crank 69 on the right side as may be seen best in Figs. 4 and 9.

Needle operating mechanism

Because it is necessary to have a needle 70 travel through a considerable path in order to clear the materials during the feeding operation, to pull sufficient thread for succeeding stitches, and to pass completely through the materials in order to cooperate with a lower looper, there is the danger of having the needle carrier 71 of considerable length. In fact most over-edge sewing machines, in which a curved needle is used, have needle carrying arms pivoted as much as three to five inches in back of the needle working point. Consequently, with such a long arm, there is considerable material to be moved each time the needle is reciprocated and the problem of adverse inertia when the machine is operated at high speeds.

The needle operating mechanism 47 comprises a needle carrier 71 having a preferably integral shaft 72 pivotally supported for arcuate movement in bearings 73 and 74 on the underside of a top housing 75 secured to the work plate 30 by screws 76, as may be seen best in Figs. 2 and 5. The needle 70 may be clamped in a suitable hole in the carrier 71 by a nut 71'. The top housing is provided with depending lugs 77 and 78 forming the bearings 73 and 74 to pivotally or arcuately support the shaft 72 of the needle carrier 71. A rearwardly extending arm 79 is secured to the shaft 72 by a yoke 80 and screw 80' to hold an eccentric 81 against the left side of the housing 75 and thereby prevent axial movement of the shaft.

In order to impart oscillatory movement to the needle 70 and carrier 71 from the raised inoperative position shown in Fig. 3 to the lowered operative position (not shown), the present invention provides a very short crank connection 82 comprising a crank-arm 83 secured to the crank 68 as by a conventional cap 84 and screws 84' and joined by a pivot stud 85 to the rearwardly extending arm 79, as may be seen in Figs. 7 and 9, thus providing very short and substantially direct driving connections with very little inertia.

Trimming mechanism

The trimming mechanism 42 is best seen in Figs 1, 2, and 3. In the preferred form it comprises an upper movable cutter 86 having an adjustable connection with a cutter carrier arm 87 mounted for pivotal and axial movement on a shaft 88 which has pivotal and axial movement in upstanding lugs 89 and 90 on the work plate 30. Although the cutter carrier arm 87 is of substantial length, a driving connection 91 is intermediate its length, remote from the shaft 88 and close to the cutter 86, so that the arm will not yield or vibrate to the same extent as it would if the driving connection 91 extended to the shaft 88 rather than the arm, or were located behind the shaft.

A lower cutter 92 (best seen in Fig. 1) comprises a blade secured in a lower cutter carrier 93 as by suitable holding screws 94. The lower cutter carrier is provided with a tongue 95 entering a channel 95' in a retaining plate 96 secured to a depending front wall 97 on the work plate. This channel permits the carrier to be slid transversely relative to the line of feed. A spring 98 yieldingly urges the lower cutter 92 in good

shearing engagement with the upper cutter 86. A depending finger on the upper cutter is always in engagement with the lower cutter 92 so that the spring 98 will not push the lower cutter out of shearing engagement or into a position directly underlying the upper cutter. This structure is shown most clearly in my co-pending application Serial No. 11,488, filed March 16, 1935.

A driving connection 91 for the upper cutter 86 comprises a pitman 100 having a bearing 101 at its lower end adapted to receive the eccentric 81 on the shaft 72 of the needle carrier 71 and at its upper end having a pivotal connection 102 to the cutter carrier arm 87 as by a stud 103. The bearing 101 may be made integral with the pitman 100 so that the eccentric 81 may be slid into the bearing prior to tightening the arm 79 on the shaft 72.

Fig. 5 clearly illustrates how the stud 103 has an axially sliding fit with a bore 103' in the cutter carrier 87 so that the trimming mechanism 42 may be shifted laterally relative to the needle. As the needle carrier 71 is oscillated, the eccentric 81 through the crank-arm 83 imparts absolute coordinate movement to the carrier 87 and cutter 86.

Presser device

The presser device 44 which may be seen best in Figs. 1, 2, and 3, comprises a carrier 104 secured on a rod 105 by a screw 106, the rod having axial and rotary movement in upstanding lugs 89 and 90 on the upper side of the work plate 30. The carrier block is provided with a finger 107 having a channel 108 adapted to receive a spring carrier-arm 109 and to locate it against lateral displacement while a screw 110 holds it against vertical displacement relative to the block. Divers presser feet 111 may be secured to the front end of the spring carrier-arm.

The main pressure of the presser foot toward the work plate is accomplished by a coil spring 112 located in a suitable bore in the carrier block 104 as may be seen best in Fig. 2, preferably having a ball 113 at the lower end adapted to slide over the work plate 30. A screw stud 114 permits various pressure adjustments.

An arm 115 extending rearwardly of the carrier block 104 is provided to lift the presser foot into an inoperative position relative to the work plate 30. Preferably, it is provided with any usual type of foot treadle connection. The presser device is more completely described, shown and claimed in my copending application Serial No. 86,922, filed June 24, 1936.

Feeding mechanism

Figs 3, 4, 6, 7, and 10 particularly show a differential feeding mechanism 50 comprising a feed dog carrier 117 having a pivotal connection 118 with a sleeve 119 on a feed rocker frame 120. A primary feed dog 121 is at the front end of the carrier 117. A differential feed dog 122 may also be slidably secured thereto by a screw 123. Both feed dogs reciprocate in a slot 124 in a needle plate 125. Substantially midway of its length the carrier 117 is provided with a feed-lift connection 126 (Figs. 6 and 9) including a split bearing 127 fitting upon the crank 66 of the main drive shaft 46 which in turn slides in an elongated slot 129 (Figs. 6 and 9).

A feed rocking connection 130 is provided to impart variable extents of movement to materials on the work plate 30 under the presser de-

vice 44 and relative to the needle 70 and primary feed dog 121. Main feed rocking movement of the carrier 117 and primary feed dog 121 secured thereto, is effected by a rearwardly extending crank-arm 131 connected to the adjustable eccentric 64 by a bearing 132 at the front end and at the back end by bearing 133 to the sleeve 119 on the rocking frame 120 which is pivoted on the sleeve 134 in bearings 135 and 136 on the web 137 and wall 57 of the work plate 30. By moving the eccentric 64, less and greater feed rocking movement is imparted to the frame 120 and carrier 117.

The mechanism for moving the differential feed dog 122 (Figs. 3, 7, 9, and 10) comprises the mechanism just described and a forwardly extending crank-arm 138 connected to the eccentric 64 at one end, and at its other end having a pivot connection 139 with a block 140 slidably mounted on a link 141. The link is, by a stud 142, link 143, and screw 123 at its upper end connected to a differential feed dog carrier 144 which is slidable in a slot 145 in the main carrier 117. At its lower end the link 141 is pivoted on a stud 146. Divers differential feed dogs 122 may be connected to the differential feed dog carrier 144. Viewing Fig. 3 it will be seen that the connection 138' extending from the driving crank 138, and the slide block 140 can be shifted up and down on the curved arm 141 to effect different extents of feed movement of the feed dog 122 even though the eccentric 64 and travel of feed dog 121 are not changed.

Shifting of the slide block 140 into various stations in order to effect a differential feed is preferably accomplished instantaneously, without the use of hands, and without the necessity of lifting the work plate 30 from the main frame 20 by the provision of a control arm 147 pivotally mounted on a stud 148, having a spring strip connection 149 under screws 150 and 151 to the slide block and having a pin and slot connection 152 with a stud 153 and outer lever 154 pivotally mounted on the left side wall 24.

This feeding mechanism is claimed and is much more completely shown and described in my copending application Serial No. 27,773, filed June 21, 1935.

Looper mechanism

The looper mechanism 48 may be seen best in Figs. 3, 4, 5, 6, and 10, and comprises a lower looper mechanism 48a and an overedge looper mechanism 48b, the latter having a retracted position under the work table 30 and an advanced operating position above the work table and materials being sewed (shown respectively by full lines and dot and dash lines in Fig. 10). This looper mechanism is capable of forming a usual single, double, and triple thread seam, type 501, 502, 503, 504, and 505 "Federal specification for stitches, seams, and stitching".

The lower looper mechanism 48a (Figs. 4, 5, and 10 particularly) comprises a looper carrier arm 155, supporting a looper 156, on a shaft 157 pivotally mounted in a bearing 158 of a depending housing 160, and having an arm 161 extending laterally of the machine to a crank connection 162 with a crank 69 on the main drive shaft. Preferably, the connection comprises a crank-arm 164 with a ball and socket joint 165 at the upper end and a similar ball and socket joint 166 at its lower end. The lower looper 156 is secured to the looper carrier 155 by screws 167 and may be readily interchanged for other slight-

ly different shaped loopers when the size of the thread, materials being operated upon, stitch, or other similar factors make such change desirable.

The overedge looper mechanism 48b comprises a looper carrier 168, interchangeably supporting a looper 169, on a shaft 170 shown in Figs. 4, 5, and 6, and which has a secondary arm 171 with a crank connection 172 to the crank 67 on the main drive shaft. The crank connection preferably includes a crank-arm 174 having a ball and socket joint 175 at its upper end to the crank 67 at one end, and a similar ball and socket 176 joint to the arm 171 at its lower end. The shaft 170 is journaled in a bearing 177 of the depending housing 160. The carrier 168 supports a looper 169 on a pivot 178 which has a secondary pivotal connection 179 intermediate its length on a crank-arm 180 portion of a shaft 181. This looper mechanism imparts both a vertical and oscillatory movement to the looper 169 from the full line to the dot and dash line position shown in Fig. 10.

In general, and dependent upon the type seam desired, the lower looper mechanism 48a may carry a hook-type looper or an eye-type looper, and the overedge looper mechanism 48b may carry a hook-type overedge looper or an eye-type overedge looper.

Thread tensioning control

A single finger 182 on the top of the crank arm 164 oscillates and reciprocates within a guide plate 183, having apertures to receive the three threads, once each time the needle 70 and loopers are actuated, and in synchronism therewith, to take up the slack thread as the needle and loopers move toward the retracted position. The puller rod 184 builds up a slack in the needle thread. The take-up finger 182 is both oscillated and reciprocated in an opening 185 in the top plate 30.

The thread control mechanism 43 is much more completely described in my copending application Serial No. 118,061, filed December 29, 1936.

Lubricating system

The present invention provides a very novel lubricating system 186 and should therefore be particularly noted, from the detailed description which follows.

Attention is directed to a highly efficient oil storage and distributing structure 187 embodied in the work plate 30 comprising a main oil duct 188 extending transversely across the work plate 30 adapted to store lubricant 26 and to direct it to various distributing structures. Oil or other lubricant is supplied to this main duct by a co-extensive feeder duct 189 extending downwardly to a pump 190 secured in the side wall 25 by a screw 191.

The pump may be operated by the back of a belt (not shown) which drives the main pulley 61, and is adapted to draw oil from a sump 192 through an inlet port 193 and to force it upwardly through the feeder duct 189 to the main duct 188.

Of particular importance, the feeder duct is provided with an enlarged bore 194 (Figs. 4 and 6) adapted to receive a cork or like sleeve insert 195 having a top face 196 adapted to receive a lower face 197 on the work plate 30. A bore 198 in the insert conducts oil and the faces 196 and 197 form an effective joint adapted to allow the work plate to be moved about the pivot con-

nection 31 to a raised inoperative position, without disconnecting pipes, threaded unions, or the like, and without the use of special tools, and to form an effective joint and oil seal when the 5 work plate is lowered into the operative position shown in Figs. 1, 3, and 4.

One means for distributing oil from the main duct 188 includes a small outlet 199 with vanes 200 and 201 on the underside of the work plate 30, as shown in Fig. 11, with the outer extremities thereof respectively overlying oil entrance holes 202 and 203 in the yoke 120 and crank-arm 174 to effectively oil the crank and yoke, when oil flows out of the aperture 199 and runs by 15 gravity to the lower and outer extremities of the vanes and drops therefrom. Excess oil dropped onto the top of the crank-arm 174 may run downwardly along the crank to oil the lower bearing 176 thereof, and oil dropping from the 20 vane 200 thoroughly lubricates the bearings underlying it.

Similarly, vanes 204 and 205 associated with an aperture 206 in the main duct 188 are adapted to direct and drop oil or other lubricant respectively onto the top bearings at the left side of the yoke 120 and into a channel 207 at the top of the feed dog carrier 117 (Figs. 6 and 7). Oil passes from the channel 207 to the top and bottom faces 208 and 209 of the elongated slot 30 129 portion of the feed dog carrier 117 which slidably supports the slide bearing 127. Other vanes may be provided on the underside of the work plate in order to direct oil to other parts of the mechanism. Holes 208' and 209' pass oil 35 to the bearing 127.

Force feed lubrication to important bearings and moving parts is also accomplished according to the present invention by providing a distributor duct 210 extending from the main duct 188 to a point adjacent the suspended housing 160 supporting the upper looper mechanism 48b and lower looper mechanism 48a (see Figs. 3, 4, 5, 6, and 10). Oil is ejected from the aperture 211 into the chamber 212 section of the housing and as it moves downwardly therein, it enters apertures 213, 214, and 215 in sleeves 157', 170', and 181' to lubricate the shafts 157, 170, and 181 respectively. Thus, thorough lubrication of the looper bearings is insured.

If preferred, a plate 217 may be snapped and held in a channel 216 on the underside of the depending housing 160 to change the chamber 212 from an open one as shown in Figs. 5 and 6 to a closed one as shown in Fig. 3. In the latter event, oil flows out over the top edge 218 (Figs. 6 and 7) when the chamber is filled. In practice it has been found that adequate lubricant is received on the bearing even though the bottom plate is not provided.

A novel structure is also provided to force feed lubricate both the needle and trimmer mechanisms 47 and 42 respectively. A distributor duct 219 (Figs. 2 and 7) extending from the main duct, has an upwardly extending outlet 220 (see Fig. 8) communicating with channels 221, 222, and 223. The channel 221 extends to a pocket 224 (Figs. 5, 7, and 8) communicating with an open end in the rocker shaft 72 of the needle-carrier 71, as shown in Fig. 5, and passes lengthwise in a bore 225 to outlet apertures 226, 227, 228, and 229 to lubricate bearings 73 and 74 of the rocker rod and the bearing 101 of the eccentric 81.

The channel 222 extends to a point above the ball bearing 53 where it has an outlet port 230

(Figs. 8 and 9) communicating with a channel 231 to carry oil to the ball bearing. As the oil flows from the outlet port 230, it flows over the side of the bearing and into the ball race to lubricate the same. An oil retainer 65 prevents 5 the oil from leaking therethrough.

Similarly the channel 223 extends to a point above the center bearing 51 where it has an outlet port 235 communicating with a hole in the split bearing to lubricate section 236 of the 10 shaft 46. If preferred, and as shown in Fig. 9, the shaft 46 may be provided with a groove 237 and aperture 238 and a coextensive duct 239 adapted to force feed oil to cranks 67, 68 and 69 through suitable outlets. 15

The open side of channels 221 and 223 (as viewed in Fig. 8) is closed when the housing 75 is set above them and secured in place by screws 76. A gasket 241 is preferably provided between the underside of the housing and the top of the 20 work plate. Also, a gasket 242 having a snug fit between the end of the rocker rod and the wall 243 of the pocket 224 prevents adverse oil leakage at this point. Any suitable aperture in the gasket 242 allows oil to enter the bore 225. 25

A separate and similar distributor duct 244 may be provided to direct oil from the main duct 188 to the ball bearing 53 to force feed lubricant thereto. As shown in Figs. 4, 7, and 9 this duct 244 extends to a point above the bearing where 30 it has a coextensive downwardly extending duct 245 joining a channel 246. Thus, oil may be forced from the main duct 188 through the distributor duct 244, thence through the duct 245 and channel 246, to run down over the side of 35 the ball bearing 53, or over both sides thereof, and enter the ball race. By omitting the retainer 65 and having the channel 246 extend fully through the wall 59, oil will be passed into the bearing from two sides. 40

Preferably a chamber 248 is provided near the outer end of the main oil duct 188 with a glass 249 sealing the top thereof to give a visual indication of whether oil is flowing therethrough, and with a member 250 (Figs. 3 and 19) secured to 45 the underside of the top plate with a screw 253 and having a struck up section 254 adapted to substantially seal the bottom of the chamber but having a notch 254' and a channel 251 adapted to pass and direct oil from the chamber 248 to 50 operating parts such as the main operating connections of the feeding mechanism which underlie its outer end 252.

As described in detail hereinbefore, the outer walls 22-24 of the main frame 20 are preferably 55 provided with a gasket 37 on their top edge adapted to prevent oil from leaking out of the main frame onto the adjacent work bench, and to form a noise insulator. In order to form a more effective seal and to provide additional protection 60 against such adverse leakage, the present invention provides a plurality of depending walls 57, 58, 59, 255, and 256, any or all of which direct oil thrown off by the driving mechanism 50 back onto the driving mechanism or downwardly into 65 the oil reservoir. Thus, the amount of oil reaching the gasket 37 is greatly reduced and the danger of oil leakage minimized.

The walls 57, 58, and 59 support the bearings 51, 52, and 53, and also enclose ducts carrying oil 70 to said bearings. One of the main advantages of the suspended inner walls is that they prevent oil from being thrown against the carrier slide 93 and thence passed outwardly of the machine at this point which is less effectively sealed than 75

the full solid side walls. Preferably, all four inner walls 58, 59, 255, and 256 are provided to completely encircle the main driving mechanism, and with the outer walls provide a very advantageous means to prevent oil from adversely getting onto the outside of the machine or onto the adjacent work bench.

These inner walls also serve the important purpose of confining and directing fine oil mist, created when oil is thrown off by the high speed moving parts to escape apertures 257 and 258 (Figs. 2, 12 and 20) underlying rods 105 and 88 to lubricate these rods in the bearings thereof located in the upstanding lugs 89 and 90. Fig. 20 discloses a rod 105a having a series of small longitudinal channels 285 and 286 with associated helical main channels 287 and 288 preferably within sleeves 289 and 290 or other suitable bearings. These channels may be given divers shapes. Preferably the channels 287 and 288 conduct the bulk of oil downwardly around the rod 105a from the top of the oil apertures 257, or oil mist upwardly from the same apertures, while at the same time the channels 285 and 286 take the oil from the main channels 287 and 288 to distribute it lengthwise of the rod. Preferably, the helical or main channels 287 and 288 are arranged so that cross channels 287' and 288' align with the apertures 257 to insure a freer conducting passage of lubricant to the various channels. The same structure may be used to lubricate the rod 88 and other bearings. This is a very effective structure for lubricating bearings.

The inner walls direct oil mist upwardly through the aperture 185 to be deposited on threads being passed through the overlying thread guide 183. Since the threads are always of comparatively small diameter and pass through the guide at a very high speed, they collect but an infinitesimal amount of oil mist, just enough to facilitate the threads passing through and over subsequent guides and thereby minimize thread breakage, and not enough to discolor, stain, or otherwise mar the materials sewed.

As shown in Figs. 4, 6, 7, 9, and 10 a screen 292, stretched and supported by a rectangular frame 293 adjacent walls of the frame 20, and completely overlying the reservoir 26, is provided to catch lint and filter lubricant dropping from all parts of the driving mechanism and work plate. Thus, all lubricant may be thoroughly filtered before reaching the pump 196. The screen may be removed easily for cleaning when there is an accumulation of lint and other undesirable matter.

The ducts 210, 219, and 244 according to the present invention may be cored and cast integral with the work plate 30 (as shown in the work plate 30' of Figs. 12, 13, and 14) between the top and bottom faces 260 and 261 respectively. Thus, there is provided a very economical structure for guiding and distributing lubricant to various predetermined locations, and one in which there is no danger of kinking or splitting tubes or loosening soldered or threaded connections as can occur when usual open or exposed pipes are provided. Except for the cast ducts 188, 219, 210, and 244 this top plate 30' and all of the associated parts are the same as the plate 30 (Figs. 1-11) already described in detail.

Preferably, the main duct 188 and distributor ducts 210, 219, and 244 are formed by casting an interconnected pipe system 264, shown in Figs. 15-18, within the top plate 30 between the top and bottom faces 260 and 261. However, very

special problems are involved in making this structure and the present invention provides a novel method of constructing this oiling system.

Method

Difficulties are sometimes encountered when effort is made to core long small holes in castings, and sometimes air holes or other like imperfections extending to a duct formed by a cored hole allow adverse escape of fluid. While these disadvantages do not occur very often, it is preferable to have ducts formed with pipe linings. However, until the present invention, so far as applicant is aware, this has not been possible since molten metal of the casting would fill the pipes.

The present invention provides a very advantageous method of making a preferred oiling system with pipes cast within a work plate 30 or the like without danger of filling, or partly filling any of the pipes which would thereby render the system inoperative.

This method includes as a first step the cutting and forming of pipes to the shape of the desired ducts. In the form shown in ducts 188, 25 210, 219, and 244 are formed by pipes 188', 210', 219', and 244'. A second step comprises closing the ends of pipes. This may be accomplished by inserting plugs into the bores of the pipes at the ends thereof, or as shown may be done by simply crushing or flattening the ends. Closed ends 265 and 266 on the pipe 219', closed ends 267 and 268 on the pipes 210' and 244, respectively, see Figs. 15-18, absolutely prevent molten metal from entering at these points.

A third step consists of laying or securing the tubes together in spaced relation to each other. Preferably, the laid together pipes are welded as at 269 and 270 to make the interconnected pipe system 264 shown in Figs. 15 and 16. If preferred, the order of the second and third steps may be reversed, for it may be preferred to close the ends after the pipes are laid together. Also, the third step may be omitted entirely, as when only one tube is to be cast in place to form a duct.

As a fourth step, the pipe system 264 is cast within the work plate 30 between the top and bottom faces 260 and 261 thereof. A pair of studs (not shown) in the conventional die for forming the work plate, entering bores 271 and 272 of the pipes 188' and 244' at the ends thereof, serves satisfactorily to hold the pipe system in place and between the faces 260 and 261 during the casting thereof, so that the pipes are cast within the work plate, and also prevents molten metal from entering at these two open places in the system.

A fifth step consists of drilling or otherwise machining oil escape apertures in the various pipes. In the form shown, this comprises drilling apertures 199 and 206 associated with oil distributing webs 200, 201, 204, and 205 as hereinbefore described; drilling an aperture 273 to form an aperture between the pipes 219' and 188', and an aperture 274 through the outer end 65 of the pipe 219' enables the latter pipe to transmit lubricant to the outlet 220 and channels 221, 222, and 223 for distribution as hereinbefore described (preferably the lower section of apertures 273 and 274 are sealed with plugs 275 70 and 276); similarly drilling an aperture 278 to complete an oil transmitting channel from the main duct 188 and pipe 188' to the bearing 53—and preferably plugging the lower section of the aperture 278 with a plug 279; drilling or coun-

terboring the chamber 248 so that lubricant may be passed into view under the glass 249 and passed outwardly of the chamber through a notch 254' for distribution by the channel 251; and, 5 drilling an aperture 211 into the outer end of the pipe 210' (Fig. 7) so that oil may be transmitted to the chamber 212 of the suspended housing 160 to oil the shafts 157, 170, and 181 and the like as hereinbefore described in detail.

10 It is within the purview of this invention to provide either a greater or smaller number of distributing ducts 188, 210, 219, and 244 (pipes 188', 210', 219', and 244'). By drilling various sizes of apertures 199, 206, 211, 254', 273, 274, 15 and 278, extent of lubricant distribution to various points may be closely regulated and positive supply of lubricant to the most remote points in the system may be insured.

Cover

20 If preferred, all the movable operating parts on the top of the work plate 30 or 30' according to the present invention, may be substantially enclosed with a cover 384 in order to protect the 25 operator from the cutter 86, needle 70, and both the needle and trimmer operating mechanisms which are moved at very high rates of speed; also, to guard against the possibility of an operator dropping a screw driver or any other thing 30 down into the rapidly moving parts. It is particularly advantageous in enabling the operator to use his hands to move the work closer to the operating parts with safety.

The cover may be made of sheet metal, cast 35 iron, or various other materials. Preferably, though, it is made of molded transparent Bakelite, or shaped Celluloid, so that it is possible for the operator to thoroughly check up on the operation of the various parts and the movement of the thread and the like through the 40 various guides and tensioning devices, even though the cover encloses all the upper moving parts.

The cover 384 is more completely shown in 45 Figs. 1 and 3, and in complementary, though in lesser degree, by dot-and-dash lines in Fig. 2. It comprises a top 385, front and rear walls 386 and 387, and also left and right side walls 388 and 389. The lower edge of one or more of 50 these walls may be provided with a cushioning member 390, of rubber, leather, or the like to insure good fit between the cover and the work plate and particularly to prevent the possibility of minor vibrations in the sewing machine being 55 developed into major adverse resonant noises in the cover.

Of particular importance, the inside of the cover 385 is provided with depending walls 391, 392, 393, and 394 having one or more suspended 60 tips 395 which serves to collect the oil mist which rises out of the work plate openings 185, 257, and 258 into drops of oil on tips 395 adapted to direct or drop the collected oil onto various underlying bearings. Additional tips for collecting and dripping oil onto additional moving parts may similarly be provided.

The cover may be held on the work plate in various ways. In its present preferred form it is provided with a snap-connection 296 adapted 70 to pivotally secure the rear wall 387 of the cover to the shaft 105 of the presser device, between the carrier block 104 and the lug 89.

Variations and modifications may be made within the scope of this invention and portions 75 of the improvements may be used without others.

Having thus described the invention, what is claimed as new is:

1. In a sewing machine the combination of a main frame forming an oil reservoir; a work plate on said main frame; a pump; main driving mechanism supported by said work plate; ducts integral with said work plate and associated with said pump adapted to direct oil onto the main driving mechanism underlying said work plate; a chamber associated with said ducts; and a member underlying and sealing said chamber and adapted to conduct oil therefrom to parts of the driving mechanism. 10

2. In a sewing machine the combination of a main frame forming a reservoir for lubricant; a work plate on said main frame having operative and inoperative positions relative thereto; a pump; main driving mechanism underlying said work plate; ducts within said work plate adapted to direct lubricant to said driving mechanism; a 20 feeder duct joining said pump to the ducts within the work plate; and a cork insert in said feeder duct and forming a lubricant conducting portion thereof, adapted to complete the feeder duct association with the ducts in the work plate and adapted to allow the work plate to be freely moved into and out of operative position. 25

3. In a sewing machine the combination of a main frame having an oil reservoir; a work plate on said main frame, having an oil conducting 30 channel with an open end; a shoulder in said channel adjacent said open end; a needle operating mechanism; a rocker shaft in said needle operating mechanism, having an oil conducting bore with at least one outlet; a bearing for said 35 shaft; an apertured gasket located in said channel between said shoulder and an end of said shaft; and means for directing oil from said oil reservoir into said channel in the work plate to pass through said bore and said outlet to said 40 bearing.

4. In a sewing machine the combination of a main frame; a work plate; a depending housing on said work plate; lubricating means; sewing mechanism; a main pivotal mounting for a lower 45 looper; a main pivotal mounting for an overedge looper; an intermediate pivotal mounting for said overedge looper; and a depending housing on said work plate supporting said pivotal mountings; and means on said depending housing adapted to 50 confine and direct lubricant to said pivotal mountings for said loopers.

5. In a sewing machine the combination of a frame forming an oil reservoir; a work plate on the frame having a top face and mist escape 55 apertures; operating mechanism above the top face; a cover plate on the work plate; vanes within said cover plate adapted to collect mist passing upwardly through said mist apertures and to direct it onto predetermined parts of said 60 operating mechanisms.

6. In a sewing machine the combination of a main frame; a work plate having a mist escape aperture; means for creating an oil mist beneath said work plate; and a thread guide associated 65 with said mist aperture to lubricate threads passing through the guide.

7. In a sewing machine the combination of a shaft; a bearing for said shaft and having an oil entrance aperture; a helical channel on said shaft 70 cooperating with said entrance aperture to carry oil around the shaft; and a plurality of small longitudinally extending channels associated with said helical channel for conducting oil lengthwise of the shaft. 75

8. In a sewing machine the combination of a main frame; a work plate on said main frame, having a top and a bottom face; driving mechanism below said work plate and supported thereby; a pair of superposed pipes for conducting oil to said driving mechanism and having contiguous portions, cast within said work plate between the top and bottom faces thereof, said work plate and said contiguous portions of said pipes being cut to provide communicating apertures; and a sealing plug closing the aperture in said work plate.
9. In a sewing machine the combination of a main frame defining a chamber; oil pumping means in said chamber; driving mechanism in said chamber; a work plate on said main frame, having a top and a bottom face, constituting a top for said chamber and overlying said driving mechanism, said work plate having at least one integral oil conducting duct extending intermediate said upper and lower faces and having at

least one aperture extending from said bottom face to said duct; and a web on said bottom face, associated with said aperture for receiving oil therefrom and directing the same to said driving mechanism therebelow.

10. In a sewing machine the combination of a main frame; oil pumping means; a main drive shaft; drive shaft bearings; sewing mechanism; feeding mechanism; a work plate having a top and a bottom face overlying said drive shaft, said bearings and said mechanism; webs for distributing oil, on the bottom face of the work plate; and pipes cast within said work plate intermediate the top and bottom face thereof, said work plate and said pipes having communicating apertures therein extending to said bottom face for directing oil to said webs, drive shaft, bearings, sewing mechanism, and feeding mechanism.

JOHN P. WEIS. 20
